[57] CLAIM

The ornamental design for a jewelry ornament, as shown.

DESCRIPTION

FIG. 1 is a perspective view of a jewelry ornament showing my new design; the broken line showing of a jewelry member and mounting hardware therefor is for illustrative purposes only and forms no part of the claimed design; FIG. 2 is a front elevational view thereof; FIG. 3 is a rear elevational view thereof; FIG. 4 is a right side elevational view thereof; FIG. 5 is a left side elevational view thereof; FIG. 6 is a top view thereof; FIG. 7 is a bottom view thereof; and, FIG. 8 is the perspective view of FIG. 1 with display members in partial rotation to further illustrate my design.
